UNITED STATES PATENT OFFICE

ALFRED C. GUNSAULUS, OF AKRON, OHIO, ASSIGNOR TO THE GOODYEAR TIRE & RUBBER COMPANY, OF AKRON, OHIO, A CORPORATION OF OHIO

DESIGN FOR A TIRE

Application filed May 2, 1932. Serial No. 43,690. Term of patent 3½ years.

To all whom it may concern:

Be it known that I, ALFRED C. GUNSAULUS, a citizen of the United States, residing at Akron, in the county of Summit and State of Ohio, have invented a new, original, and ornamental Design for a Tire, of which the following is a specification, reference being had to the accompanying drawing, forming part thereof.

Fig. 1 is a top plan view of a portion of a

tire casing embodying the present design; Fig. 2 is a fragmentary side elevation of the same;

Fig. 3 is a cross sectional view on the line 3—3 of Figure 1; and

Fig. 4 is a fragmentary perspective view of a tire embodying my design.

I claim:

The ornamental design for a tire, as shown.
ALFRED C. GUNSAULUS.
